UNITED STATES PATENT OFFICE.

WILLIAM HELMER, OF BOSTON, MASSACHUSETTS, ASSIGNOR TO AMERICAN SODA FOUNTAIN COMPANY, OF BOSTON, MASSA-CHUSETTS, A CORPORATION OF NEW JERSEY.

DESIGN FOR A DRINKING-GLASS OR SIMILAR ARTICLE.

No. 38,248.

Specification for Design.

Patented Sept. 25, 1906.

Application filed July 30, 1906. Serial No. 328,485. Term of patent 7 years.

To all whom it may concern:

Be it known that I, WILLIAM HELMER, a citizen of the United States, and a resident of Boston, in the county of Suffolk and State of Massachusetts, have invented a new, original, and ornamental Design for a Drinking-Glass or Similar Article, of which the following is a specification, reference being had to the accompanying drawing, forming a part hereof, which is a perspective view of said design.

What I claim is—
The ornamental design for a drinking-glass or similar article as shown.

WILLIAM HELMER.
